FUEL SYSTEM

Robert J. Powell and James E. Champion, Muskegon, Mich., assignors to Continental Motors Corporation, Detroit, Mich., a corporation of Virginia

Application February 13, 1957, Serial No. 640,044

15 Claims. (Cl. 158—36.4)

Our invention relates to internal combustion engines, and more particularly to fuel delivery systems therefor and comprising a vapor separator.

The problems encountered when vapors are permitted to circulate in a fuel delivery system are well known, particularly the phenomenon of vapor lock caused by the expansion of vapors due to the heat of the internal combustion engine, and preventing fuel from getting to the engine. In aircraft engines particularly this condition may be extremely dangerous. Heretofore, the methods and devices provided for separating and eliminating vapors from the fuel lines have been, if successful at all, rather complicated and expensive. Further, the presence of vapor in the fuel materially affects the fuel metering and makes it impossible to meter the fuel with a degree of accuracy as required by aircraft engines. It will thus be readily appreciated that entrapped vapor in the fuel is not desirable and it can result in very poor engine performance.

An object of the present invention is to eliminate vapors from the fuel delivery system of an internal combustion engine by providing a simplified centrifugal vapor separator upstream of the fuel pump.

Another object of the invention is to prevent vapor lock in engine fuel delivery systems by constructing a centrifuge chamber having the fuel inlet from the fuel tank and outlet to the fuel pump tangentially arranged to induce centrifugal vapor separating motion in the chamber.

A further object of the invention is to provide improved means for vapor separation in fuel delivery systems by constructing a centrifugal separating chamber having a vapor outlet connected with a venturi in a fuel line returning to the fuel tank.

A still further object of the invention is to improve fuel delivery systems by providing a compact, simplified pump, vapor separator, and relief valve assembly, and including an emergency bypass system operable to insure vapor-free fuel delivery in the event of fuel pump failure.

A more complete understanding of our invention may be had by reference to the accompanying drawings illustrating a preferred embodiment of the invention in which like reference characters refer to like parts throughout the several views and in which—

Fig. 1 is a diagrammatic representation of a preferred fuel system incorporating the invention.

Fig. 2 is a side elevational view of the fuel pump, vapor separator, and relief valve assembly embodied in the fuel system of Fig. 1.

Fig. 3 is an elevational view showing the left end of the assembly of Fig. 2.

Fig. 4 is an elevational view of the vapor separator with the cover removed as seen substantially from the line 4—4 of Fig. 2.

Fig. 5 is a view of the vapor separator partially in section as viewed from the left side of Fig. 4.

Fig. 6 is a top view of the vapor separator of Figs. 4 and 5.

Fig. 7 is an elevational view of the vapor separator as

2

viewed from the left side of Fig. 5 and substantially from the line 7—7 of Fig. 2.

Fig. 8 is an elevational view of the vapor separator as seen from the left side of Fig. 7.

Fig. 9 is a cross-sectional view taken substantially on the line 9—9 of Fig. 4.

Fig. 10 is a cross sectional view taken substantially on the line 10—10 of Fig. 8.

Fig. 11 is an inner view of the vapor separator cover partially in section, as seen substantially from the line 11—11 of Fig. 3, and

Fig. 12 is an elevational view of the cover as seen from the right side of Fig. 11.

Referring to Fig. 1, a fuel system is illustrated for an internal combustion engine having an air induction system 10 including a throttle valve 11 and air intake manifold 12. The fuel system is preferably of the fuel injection type comprising a fuel tank 13, a fuel pump, vapor separator, and relief valve assembly 14, a metering device 15 operable connected to the throttle valve 11 by any means for such as linkage 16, and a fuel distribution valve 17 for distributing fuel to injectors 18.

The assembly 14, seen also as a unit in Figs. 2 and 3, comprises a conventional fuel pump 25, a vapor separator 26 having a casing 27 and cover 27a, and a conventional pressure relief valve 28. The pump 25, vapor separator 26, and relief valve 28 are preferably assembled together by bolts 29, and the cover 27a is preferably secured to the vapor separator by screws 30.

An auxiliary fuel pump 31 is preferably disposed in the fuel tank 13 as shown in Fig. 1 and is operable to pump fuel through a conduit 32 or other conducting means through a filter 33 to an inlet 34 in the vapor separator casing 27. The casing 27 is provided with a substantially vertically disposed cylindrical centrifuge chamber 35. The inlet 34 is arranged to deliver fuel into the chamber 35 substantially tangentially with respect to the chamber wall and at a point near the upper end of the chamber 35 as illustrated in Figs. 8 and 10. A fuel outlet passage 36 is provided in the casing near the lower end of the chamber 35 and is also arranged substantially tangentially with respect to the chamber wall as shown in Figs. 4, 5, 6 and 9. The outlet passage 36 opens on the face of the casing 27 which abuts the fuel pump 25 and is arranged to connect with the intake thereof.

The fuel pump 25 discharges fuel under pressure through an outlet 40 into a fuel delivery conduit 41 and thence to the fuel metering device 15.

The centrifuge chamber fuel inlet 34 and fuel outlet 36, being tangentially arranged, induce a rotary motion to the fuel passing through the chamber 35, causing a centrifugal force to separate the fuel and vapor, the vapor tending to collect in the upper central portion of the chamber 35 due to its lower density, and the fuel passing to the pump will then be vapor free.

A port 42 is provided in the face of the casing 37 which abuts the fuel pump and is openly connected with the discharge side of the fuel pump 25. A vertical passage 43 extends through the casing from the port 42 to the top face on which the cover 27a is secured. A vertical passage 44 in the cover 27a seen in Figs. 11 and 12 communicates with the passage 43 and connects with a diagonal passage 45 extending through the cover to an outlet port 46. A jet pump or jet syphon member 47 is disposed in the passage 45 and is connected at a lower pressure area with a passage 48 open at approximately the center axis of the centrifuge chamber.

A portion of the high pressure fuel from the discharge side of the pump which is not used by the engine passes through the passage 43 in the casing and through the passages 44 and 45 in the cover, causing vapor to be

drawn from the chamber 35 through the passage 48 into the low pressure area of the jet siphon member 47. Fuel and vapor then pass out the port 46 and through a conduit 49 or other conducting means to the fuel tank 13. A check valve 50 is preferably disposed in the conduit 49 to prevent reverse flow of vapor when the pump 25 is inoperative.

Another passage 55 extends from the port 42 laterally through the casing 27 to the face abutting the pressure relief valve 28, and communicates with the inlet thereof. A screw 56 or other device adjustably mounted in the casing 27 extends into the passage 55 to provide an adjustable restricting orifice upstream of the relief valve 28. The outlet side of the relief valve 28 communicates with a port 57 on the abutting face of the vapor separator 27. A vertical passage 58 extends from the port 57 to a slot 59 in the upper face of the casing 27 leading tangentially into the chamber 35 as shown in Figs. 5, 6 and 7. Thus excess pressure fuel relieved through the relief valve 28 is returned to the inlet portion of the vapor separator.

The fuel metering device 15 preferably includes a mixture control valve 60 operable by conventional means to bypass fuel under certain conditions, particularly at higher altitudes. Such bypass fuel is conducted by any means such as a conduit 61 to a port 62 in the casing 27, and thence to the relief valve discharge passage 58, through which it is returned to the chamber 35 by means of the slot 59.

An emergency bypass passage 65 in the casing 27, as shown in Fig. 9, connects the chamber 35 with the port 42, and is closed by a spring loaded bypass valve element 66, as shown in Figs. 4 and 9. In case of failure of the pump 25, the auxiliary pump 31 in the fuel tank 13 will continue to supply the vapor separator chamber 35, and due to decreased pressure in the port 42, the bypass valve element 66 will open, permitting fuel to flow directly from the chamber 35 into the delivery conduit 41, bypassing the pump 25.

If desired, as an aid in the operation of the vapor separator 26, a baffle element 70 may be supported in the centrifuge chamber 35 by means of a stem 71 screwed into the lower end wall of the chamber 35, all as illustrated in Figs. 4, 6 and 9. Fuel entering the chamber 35 through the port 34 and the slot 59, both disposed above the baffle 70, will be defoamed in passing over and around the peripheral edge or rim of the baffle 70 to the fuel outlet 36.

Although we have described but one preferred embodiment of our invention, it will be apparent to one skilled in the art to which the invention pertains that various changes and modifications may be made therein without departing from the spirit of the invention or the scope of the appended claims.

We claim:

1. In a fuel delivery system for an internal combustion engine, a fuel tank, a fuel pump for pumping fuel from said tank to said engine and having a capacity in excess of the fuel requirements of the engine, a fuel metering means for metering fuel to said engine, fuel conducting means connecting the intake side of said pump and said tank, a vapor separator disposed in said conducting means upstream of said pump and comprising a casing having a centrifuge chamber, a fuel inlet, a fuel outlet, a vapor outlet, and means inducing a substantially rotary motion to fuel in said chamber to centrifugally separate relatively light weight vapor and heavier weight fuel, a second fuel conducting means directly connecting the outlet side of said pump with said fuel tank to return excess fuel under pressure to said fuel tank, said vapor outlet connected with said second conducting means, and means reducing pressure at the junction of said vapor outlet with said second conducting means to a value below the pressure in said chamber, said last means being thereby operable to extract vapor from said chamber into said second conducting means, said vapor outlet disposed in

operable to extract vapor from said chamber into said second conducting means.

2. In a fuel delivery system for an internal combustion engine, a fuel tank, a fuel pump for pumping fuel from said tank to said engine and having a capacity in excess of the fuel requirements of the engine, a fuel metering means for metering fuel to said engine, fuel conducting means connecting the intake side of said pump and said tank, a vapor separator disposed in said conducting means upstream of said pump and comprising a casing having a substantially vertically extending cylindrical centrifuge chamber, a fuel inlet and fuel outlet each arranged to induce a substantially rotary motion to fuel around the vertical axis of said chamber whereby to centrifugally separate relatively light weight vapor and heavier weight fuel, a vapor outlet located substantially on the vertical axis aforesaid, a second fuel conducting means directly connecting the outlet side of said pump with said fuel tank to return excess fuel under pressure to said fuel tank, said vapor outlet connected with said second conducting means, and means reducing pressure at the junction of said vapor outlet with said second conducting means to a value below the pressure in said chamber, said last means being thereby operable to extract vapor from said chamber into said second conducting means.

3. In a fuel delivery system for an internal combustion engine, a fuel tank, a fuel pump for pumping fuel from said tank to said engine and having a capacity in excess of the fuel requirements of the engine, a fuel metering means for metering fuel to said engine, fuel conducting means connecting the intake side of said pump and said tank, a vapor separator disposed in said conducting means upstream of said pump and comprising a casing having a substantially vertically extending cylindrical centrifuge chamber, a fuel inlet and fuel outlet each arranged substantially tangentially with respect to the side wall of said chamber to induce a substantially rotary motion to fuel around the vertical axis of said chamber whereby to centrifugally separate relatively light weight vapor and heavier weight fuel, a vapor outlet located substantially on the vertical axis aforesaid, a second fuel conducting means directly connecting the outlet side of said pump with said fuel tank to return excess fuel under pressure to said fuel tank, said vapor outlet connected with said second conducting means, and means reducing pressure at the junction of said vapor outlet with said second conducting means to a value below the pressure in said chamber, said last means being thereby operable to extract vapor from said chamber into said second conducting means.

4. In a fuel delivery system for an internal combustion engine, a fuel tank, a fuel pump for pumping fuel from said tank to said engine and having a capacity in excess of the fuel requirements of the engine, a fuel metering means for metering fuel to said engine, fuel conducting means connecting the intake side of said pump and said tank, a vapor separator disposed in said conducting means upstream of said pump and comprising a casing having a substantially vertically extending cylindrical centrifuge chamber, a fuel inlet and fuel outlet each arranged substantially tangentially with respect to the side wall of said chamber to induce a substantially rotary motion to fuel around the vertical axis of said chamber whereby to centrifugally separate relatively light weight vapor and heavier weight fuel, said casing having a vapor outlet located substantially on the vertical axis aforesaid, a second fuel conducting means directly connecting the outlet side of said pump with said fuel tank to return excess fuel under pressure to said fuel tank, said vapor outlet connected with said second conducting means, and means reducing pressure at the junction of said vapor outlet with said second conducting means to a value below the pressure in said chamber, said last means being thereby operable to extract vapor from said chamber into said second conducting means, said vapor outlet disposed in

a higher position than said fuel outlet, and said fuel inlet disposed intermediate said vapor outlet and said fuel outlet.

5. In a fuel delivery system for an internal combustion engine, a fuel tank having a supply outlet and a return inlet, a fuel pump having an intake and a delivery outlet, a fuel metering means for metering fuel to said engine, fuel conducting means connecting said tank supply outlet and said pump intake, a second fuel conducting means connecting said pump delivery outlet and said fuel metering means, and a third fuel conducting means connecting said second conducting means and said tank return inlet to return under pressure to said tank the portion of the fuel in excess of that required by said engine, a vapor separator disposed in said first conducting means and comprising a casing having a centrifuge chamber, a fuel inlet, a fuel outlet, and a vapor outlet, means inducing a substantially rotary motion to fuel in said chamber to centrifugally separate relatively light weight vapor and heavier weight fuel, said third conducting means including a jet siphon and said vapor outlet connected to said jet siphon and arranged for extracting vapor from said chamber into the third conducting means.

6. In a fuel delivery system for an internal combustion engine, a fuel tank, a fuel pump for pumping fuel from said tank to said engine, fuel conducting means connecting said pump and said tank, a vapor separator disposed in said conducting means and comprising a casing having a substantially vertically extending cylindrical centrifuge chamber provided with a top and a bottom end wall, a fuel inlet and fuel outlet each arranged substantially tangentially with respect to the side wall of said chamber to induce a substantially rotary motion to fuel around the vertical axis of said chamber whereby to centrifugally separate relatively light weight vapor from heavier weight fuel, said top end wall having a vapor outlet located on the vertical axis of the aforesaid chamber, said pump having a fuel delivery outlet for delivering fuel to said engine, said casing having a passage openly connected with said pump fuel delivery outlet and with said fuel tank for returning to said fuel tank a portion of the fuel in excess of that required by said engine, said passage including a jet siphon connected with said vapor outlet and arranged to extract vapor from said chamber into said passage for return to said tank.

7. In a fuel delivery system for an internal combustion engine, a fuel tank, a fuel pump for pumping fuel from said tank to said engine, fuel conducting means connecting said pump and said tank, a vapor separator disposed in said conducting means and comprising a casing having a substantially vertically extending cylindrical centrifuge chamber provided with a top and a bottom end wall, a fuel inlet and fuel outlet each arranged substantially tangentially with respect to the side wall of said chamber to induce a substantially rotary motion to fuel around the vertical axis of said chamber whereby to centrifugally separate relatively light weight vapor from heavier weight fuel, said fuel inlet disposed near the top end wall and said fuel outlet disposed near the bottom end wall of said chamber, said top end wall having a vapor outlet located substantially on the vertical axis of the aforesaid chamber, said pump having a fuel delivery outlet for delivering fuel to said engine, said casing having a passage openly connected with said pump fuel delivery outlet and with said fuel tank for returning to said fuel tank a portion of the fuel in excess of that required by said engine, said passage including a jet siphon connected with said vapor outlet and arranged to extract vapor from said chamber into said passage for return to said tank.

8. In a fuel delivery system for an internal combustion engine, a fuel tank, a fuel pump for pumping fuel from said tank to said engine, fuel conducting means connecting said pump and said tank and having a fuel intake in said tank, a vapor separator disposed in said conducting

means intermediate said pump and said intake and comprising a casing having a centrifuge chamber, a fuel inlet, a fuel outlet, and a vapor outlet, means inducing a substantially rotary motion to fuel in said chamber to centrifugally separate relatively light weight vapor and heavier weight fuel, and means exhausting vapor from said chamber through said vapor outlet, an auxiliary fuel pump connected with said conducting means intermediate said vapor separator and said tank fuel intake, and an emergency bypass means comprising means openly connecting said chamber with said engine and including a bypass check valve operable to open upon failure of said first fuel pump for supplying said engine with emergency fuel from said auxiliary fuel pump through said centrifuge chamber.

9. In a fuel delivery system for an internal combustion engine, a fuel tank, a fuel pump for pumping fuel from said tank to said engine, fuel conducting means connecting said pump and said tank and having a fuel intake in said tank, a vapor separator disposed in said conducting means intermediate said pump and said intake and comprising a casing having a substantially vertically extending cylindrical centrifuge chamber provided with a top and a bottom end wall, a fuel inlet and fuel outlet each arranged substantially tangentially with respect to the side wall of said chamber to induce a substantially rotary motion to fuel around the vertical axis of said chamber whereby to centrifugally separate relatively light weight vapor from heavier weight fuel, said top end wall having a vapor outlet located substantially on the vertical axis of the aforesaid chamber, said pump having a fuel delivery outlet for delivering fuel to said engine, said casing having a passage openly connected with said pump fuel delivery outlet and said fuel tank for returning to said fuel tank a portion of the fuel in excess of that required by said engine, said passage including a jet siphon connected with said vapor outlet and arranged to extract vapor from said chamber into said passage for return to said tank, an auxiliary fuel pump connected with said conducting means intermediate said vapor separator and said tank fuel intake, and an emergency bypass means comprising means openly connecting said chamber with said fuel delivery outlet and including a bypass check valve operable to open upon failure of said first fuel pump for supplying said engine with emergency fuel from said auxiliary fuel pump through said centrifuge chamber.

10. In a fuel delivery system for an internal combustion engine, a fuel tank, a fuel pump for pumping fuel from said tank to said engine, fuel conducting means connecting said pump and said tank, a vapor separator disposed in said conducting means and comprising a casing having a substantially vertically extending cylindrical centrifuge chamber provided with a top and bottom end wall, a fuel inlet and fuel outlet each arranged substantially tangentially with respect to the side wall of said chamber to induce a substantially rotary motion to fuel around the vertical axis of said chamber whereby to centrifugally separate relatively light weight vapor from heavier weight fuel, said top end wall having a vapor outlet located in said top end wall and substantially on the vertical axis of the aforesaid chamber, said pump having a fuel delivery outlet for delivering fuel to said engine, said casing having a passage openly connected with said pump fuel delivery outlet and with said fuel tank for returning to said fuel tank a portion of the fuel in excess of that required by said engine, said passage including a jet siphon connected with said vapor outlet and arranged to extract vapor from said chamber into said passage for return to said tank, and a pressure relief valve connected with said fuel delivery outlet and having a relief outlet openly communicating with said centrifuge chamber.

11. In a fuel delivery system for an internal combustion engine, a fuel tank, a fuel pump for pumping fuel

from said tank to said engine, fuel conducting means connecting said pump and said tank, a vapor separator disposed in said conducting means and comprising a casing having a substantially vertically extending cylindrical centrifuge chamber provided with a top and bottom end wall, a fuel inlet and fuel outlet each arranged substantially tangentially with respect to the side wall of said chamber to induce a substantially rotary motion to fuel around the vertical axis of said chamber whereby to centrifugally separate relatively light weight vapor from heavier weight fuel, said top end wall having a vapor outlet located substantially on the vertical axis of the aforesaid chamber, said pump having a fuel delivery outlet for delivering fuel to said engine, said casing having a passage openly connected with said pump fuel delivery outlet and with said fuel tank for returning to said fuel tank a portion of the fuel in excess of that required by said engine, said passage including a jet syphon connected with said vapor outlet and arranged to extract vapor from said chamber into said passage for return to said tank, said casing having a second passage open to said centrifuge chamber near the top end wall thereof, and a pressure relief valve connected between said fuel delivery outlet and said second passage.

12. In a fuel delivery system for an internal combustion engine, a fuel tank, a fuel pump for pumping fuel from said tank to said engine, fuel conducting means connecting said pump and said tank, a vapor separator disposed in said conducting means and comprising a casing having a substantially vertically extending cylindrical centrifuge chamber provided with a top and a bottom end wall, a fuel inlet and fuel outlet each arranged substantially tangentially with respect to the side wall of said chamber to induce a substantially rotary motion to fuel around the vertical axis of said chamber whereby to centrifugally separate relatively light weight vapor from heavier weight fuel, said fuel inlet disposed near the top end wall and said fuel outlet disposed near the bottom end wall of said chamber, said top end wall having a vapor outlet located substantially on the vertical axis of the aforesaid chamber, said pump having a fuel delivery outlet for delivering fuel to said engine, said casing having a passage openly connected with said pump fuel delivery outlet and said fuel tank for returning to said fuel tank a portion of the fuel in excess of that required by said engine, said passage including a jet syphon connected with vapor outlet and arranged to extract vapor from said chamber into said passage for return to said tank, and means disposed intermediate said fuel inlet and said fuel outlet and constructed to defoam the fuel prior to discharge to said pump and to aid in separating the vapor from the fuel.

13. In a fuel delivery system for an internal combustion engine, a fuel tank having a supply outlet and a return inlet, a fuel pump having a capacity in excess of the fuel requirements of the engine and provided with an intake and a delivery outlet, a fuel metering means for metering fuel to said engine, fuel conducting means connecting said tank supply outlet and said pump intake, a second fuel conducting means connecting said pump delivery outlet and said fuel metering means, and a third fuel conducting

means connecting said second conducting means and said tank return inlet to return under pressure to said fuel tank a portion of the fuel in excess of that required by said engine, a vapor separator connected in series with said first conducting means and having a vapor outlet, said vapor outlet connected with said third conducting means and means reducing pressure at the junction of said vapor outlet with said third conducting means to a value below the pressure in said chamber, said last means being thereby operable to extract vapor from said chamber into said third conducting means.

14. In a fuel delivery system for an internal combustion engine, a fuel tank having a supply outlet and a return inlet, a fuel pump having an intake and a delivery outlet, a fuel metering means for metering fuel to said engine, fuel conducting means connecting said tank supply outlet and said pump intake, a second fuel conducting means connecting said pump delivery outlet and said fuel metering means, and a third fuel conducting means connecting said second conducting means and said tank return under pressure to said fuel tank inlet to return a portion of the fuel in excess of that required by said engine, said third conducting means having a jet syphon passage, a vapor separator connected in series with said first conducting means and having a vapor outlet connected with the jet syphon passage in said third conducting means, whereby fuel flow in said jet syphon passage is operable to extract vapor from said separator.

15. In a fuel delivery system for an internal combustion engine, a fuel tank having a supply outlet and a return inlet, a fuel pump having an intake and a delivery outlet, a fuel metering means for metering fuel to said engine, fuel conducting means connecting said tank supply outlet and said pump intake, a second fuel conducting means connecting said pump delivery outlet and said fuel metering means, and a third fuel conducting means connecting said second conducting means and said tank return inlet to return under pressure to said fuel tank a portion of the fuel in excess of that required by said engine, a vapor separator disposed in said first conducting means and comprising a casing having a centrifuge chamber, a fuel inlet, a fuel outlet, a vapor outlet, and means inducing a substantially rotary motion to fuel in said chamber to centrifugally separate relatively light weight vapor and heavier weight fuel, said third conducting means including a jet syphon and said vapor outlet being connected to said jet syphon and arranged for extracting vapor from said chamber into the third conducting means.
